Att'y S.

UNITED STATES PATENT OFFICE

JOSEPH PAVLAS, OF CHICAGO, ILLINOIS

WIRE DISPENSER

Application filed August 13, 1929. Serial No. 385,485.

My invention relates to appliances for dispensing wire to electricians and other mechanics using a supply of one or more wires in a building, conduit, and the like, and my main object is to provide an appliance of this kind which is small in size and very handy to move about.

A further object of the invention is to provide an appliance which has a capacity for a plurality of wire reels from which one or more wires may be dispensed as desired.

A still further object of the invention is to provide a support for the wire reels which is easily removable for the installation or removal of the reels.

Another object of the invention is to supply a simple form of separator for the reels in order that each reel may turn independently as wire is drawn therefrom.

A significant object of the invention is to design the appliance with a novel form of guide for the wires dispensed, whereby the drawing of the wires in desired directions may be effected.

A final but nevertheless important object of the invention is to design the novel appliance with a minimum of sturdy and simple parts, whereby to facilitate the manufacture of the article at a reasonable cost.

With the above objects in view and any others that may suggest themselves from the specification and claims to follow, a better understanding of the invention may be had to the accompanying drawings, in which—

Figure 1 is an elevation of the novel appliance;

Fig. 2 is a section on the line 2—2 of Figure 1; and

Fig. 3 is a fragmental end view of the upper portion of the appliance.

Referring specifically to the drawings, 5 denotes a base upon which the novel appliance is erected, the base receiving heavy feet 6 for purposes of stability on a floor or other flat surface. From the ends of the base rise standards 7, these combining in a horizontal top 8 equipped with a handle 9 by means of which the appliance may be easily carried from place to place.

In order that the novel appliance may have

a large capacity, I design the same to receive a set of wire reels 10 in the upper part and a similar set of reels 11 in the lower part. Each set of reels is mounted loosely along a shaft 12 which is passed through the standards as shown, one end of the shaft being slightly pointed as indicated at 12a for facility in passing the shaft through holes in the standards. The other end of the shaft is made with a knob 12b by means of which the shaft is handled.

In order that the reels may not interfere with one another frictionally when wire is drawn from one or more of them, I provide separator plates 13 between the reels. These plates are vertically arranged and have medial apertures to clear the shaft 12; also, the plates have terminal apertures enabling them to be strung along upper and lower guide rods 14 which are riveted with their ends to the standards 7 as indicated at 14a. Thus, reels of any ordinary length may be inserted between the separator plates 13 before the shaft 12 is inserted into the structure, the separator plates sliding along the rods 14 to adjust themselves to the lengths of the reels. After a set of reels has been mounted as shown, with a slight clearance allowed between the reels and the separators for free action of the reels, the assembly may be locked by the application of a set screw 15 in a hub 16 formed outwardly from the final separator plate, so that the latter becomes firmly affixed to the shaft 12 and maintains the proper relation between the respective reels.

In order that wires may be drawn from the different reels without confusion, I prefer to pass such wires through guide plates 17 placed in front of the reels. Each guide plate is pivotally secured along a frontal rack 18, the pivot involving a screw 19 and an external wing nut 20 by means of which the angular position of any guide plate 17 may be changed and fixed. The guide plates for the respective sets of wire reels extend from the same pivotal site, each pair being lapped or doubled as indicated in the broken section of Figure 1. Thus, a single pivotal adjustment suffices for each pair of

guide plates. My intention is to have the guide openings substantially midway between the end-flanges the reels opposite them, in order to keep the wire from being caught or tangled in such flanges. Hence, the guide plates are laterally adjustable to locate the guide openings as nearly as possible in the advantageous positions mentioned.

Owing to the fact that wires are often drawn in an upward or downward direction from the reel, I have mounted the rack 18 with means whereby it may be swung upwardly or downwardly to tilt the guide plates 17 as desired and therefore facilitate the passage of the wires accordingly. For the purpose mentioned, I construct the rack 18 with terminal bends 18a which apply next outside the standards 7. At these points, the bends receive pivotal screws 19a and wing nuts 20. Thus, the manipulation of the latter will enable the rack to be lowered as indicated in Figure 2, or raised as indicated in Figure 3 to accomplish the purpose specified. The rack bends 18a are formed with inwardly projected pins 18b, and strike the standards 7 as a limit to confine the swing of the rack between desired points and keep the same from interfering with the wires from the reels.

It will be seen that the novel appliance embodies a number of features which make it a handy article for the electrician or like artisan. The device may be handily carried to any point where wire is to be dispensed and swung to a position of best advantage by the simple use of the carrying handle 9. For its size the appliance has a large capacity of wire, and may therefore be said to be a very compact magazine for the supply of the wire. Owing to the simplicity of the reel assembly, it is very easy to change, insert or remove reels; also, the handiness of the wire guides makes it an easy matter to pass the wires through the same and adjust them to the best advantage. Finally, it will be seen that the novel appliance is made of parts of extreme simplicity, facilitating the production of the same by simple methods and at a reasonable cost.

I claim:

1. A stand for wire-dispensing reels, comprising laterally-spaced standards, vertically-spaced shafts between the latter and adapted to receive groups of reels, a guide rack along one side of the stand and at a height between the upper and lower groups of reels, and wire-guiding brackets pivotally connected to the rack, said brackets being in pairs whose units are directed toward the upper and lower reel groups respectively, and said units being grouped upon the same pivot in doubled formation.

2. A stand for wire dispensing reels, comprising a pair of standards, vertically spaced reel receiving shafts mounted therebetween,

a guide rack opposite the shafts and with terminal arms leading and pivoted to the standards, and laterally spaced wire guiding brackets supported in pairs by the rack.

3. A stand for wire dispensing reels, comprising a frame, vertically spaced reel receiving shafts mounted therein, a guide rack mounted on the frame, spaced wire guiding brackets pivoted in pairs to the rack, and securing means for each pair of brackets.

In testimony whereof I affix my signature.

JOSEPH PAVLAS.
